No. 682,005.

Patented Sept. 3, 1901.

W. H. WALKER

MAIL BOX.

(Application filed June 18, 1901.)

(No Model.)

UNITED STATES PATENT OFFICE.

WILLIAM H. WALKER, OF DEGRAFF, OHIO, ASSIGNOR OF TWO-FIFTHS TO
SOLOMON E. LOFFER AND WILLIAM E. HARRIS, OF SAME PLACE.

MAIL-BOX.

SPECIFICATION forming part of Letters Patent No. 682,005, dated September 3, 1901.

Application filed June 18, 1901. Serial No. 65,038. (No model.)

To all whom it may concern.

Be it known that I, WILLIAM H. WALKER, a citizen of the United States, and a resident of Degraff, in the county of Logan and State of 5 Ohio, have invented new and useful Improvements in Mail-Boxes, of which the following is a full, clear, and exact description.

This invention relates to the type of mail-boxes employed for collection and distribution of mail by carriers, and has for its object 10 to provide a novel simple mail-box which is well adapted for collection and distribution of mail in rural districts, the device being secure, easy to operate, and provided with 15 means for indicating to a person at some distance if there is mail in the box or not.

The invention consists in the novel construction and combination of parts, as is hereinafter described, and defined in the appended 20 claims.

Reference is to be had to the accompanying drawings, forming a part of this specification, in which similar characters of reference indicate corresponding parts in all the figures.

25 Figure 1 is a perspective view of the improved mail-box. Fig. 2 is an enlarged sectional side view of the same substantially on the line 2 2 in Fig. 1. Fig. 3 is a transverse sectional view substantially on the line 3 3 in 30 Fig. 2, and Fig. 4 is a sectional plan view substantially on the line 4 4 in Fig. 2.

While the improved mail-box is available 35 for service in towns as well as in suburban districts, it is preferably employed as means for collection and distribution of mail by the carriers who traverse routes in the country, and as country residences are frequently at some distance from the public road the improved mail-box hereinafter described is very 40 advantageous in that it is not only secure against depredators and the elements, but also from the fact that it will in a very conspicuous manner positively indicate if mail-matter has been deposited in the box for delivery by the carriers or if mail-matter has 45 been placed therein by residents in the locality to be taken up by the carrier to be mailed.

In the drawings, 5 indicates a preferably metal post of any available height, to be erected 50 and fixed in the ground at a suitable point for

easy access by the mail-depositor, who may be the carrier or may be those who desire to post mail-matter. Upon the upper portion of the post 5 the box 6 is pivoted, so as to be rotatable thereon. As shown, the box 6 consists of a preferably elongated rectangular receptacle having a closure 6^a at one end, which may be water-tight, the opposite end 6^b being open. The pivot-bolt 7, that passes through the post 5 and one side wall of the 60 box 6, may be provided with a screw-nut 7^a on the end that projects inside of the box 6, and the head of the bolt may be rounded, so as to prevent easy removal of the bolt and purloining of the box and its contents. In 65 some cases it may be preferred to rivet the pivot-bolt at its ends.

Preferably to afford a substantial connection between the post 5 and box 6 two trunnion-plates 8 8^a in dished form are provided 70 and are adapted to fit one within the circular border-flange of the other, and said trunnion-plates are centrally apertured for the reception of the pivot-bolt 7, the plates 8 8^a being respectively affixed upon adjacent sides of 75 the post 5 and box 6, so that these mating trunnion-plates will support the box and its contents and afford a rotatable bearing of sufficient area for the box on the post, so as to prevent undue wear of the working parts, 80 and consequent wobbling of the box on its support.

As shown in Figs. 2 and 3, the trunnion-plate 8^a has two elongated arms d, extended oppositely in the same vertical plane, and two 85 shorter arms d², projected oppositely and horizontally. The arms d are disposed longitudinally of the box 6, on the front wall thereof, and these arms, as well as the arms d², are secured upon said wall by screws or other 90 means. Upon the side of the arms d, adjacent to the trunnion-plate 8 and near the ends thereof, two flanges d³ are formed, which project forwardly at an equal distance from the pivot-bolt 7, and in the same vertical 95 plane with the axis of the pivot-bolt a single notch d⁴ is formed in each of said flanges, and the edges of the flanges are respectively sloped away from the notches.

An arched hood 9, preferably formed of 100

metal, is secured upon the top of the post 5 and projects therefrom directly above the box 6, and, as shown, each end of the box is cut to conform to an arc of a circle having the axis of 5 the pivot-bolt 7 as a center, so that the open or closed end of the mail-box may by a half-rotation of the same be located beneath and close to the hood 9, and for the protection of the open end of the box said hood should extend 10 a proper distance beyond the side walls of the box.

Upon the side of the post 5 farthest from the box 6 a hasp-plate 10 is hinged to hang pendent, said hasp-plate having a locking-toe a projected from one side, which may pass through a slot a' , formed in the post, and also through the lock-case 11, that is bedded in the inner wall of said post, as shown in Fig. 2. A plate-spring 10^a may be provided to enable 15 the return of the hasp 10 into locking position if said hasp is swung outward. The hasp 10 is preferably provided with a flap-plate 10^b, hinged upon its lower end, and, as shown, the keyhole a^2 of the lock is so positioned as to permit the flap-plate to serve as 20 a cover for the keyhole when said flap-plate is pendent. The lock is provided with a slide-bolt 11^a, which is reciprocated within the case 11 by means of the key 11^b, of suitable form, and said lock may have other details of construction (not shown) which may be found essential to render it secure against easy picking. The toe a is notched upon its 25 lower edge, and the bolt 11^a of the lock when operated by the key 11^b may be slid through the notch c , which will hold said toe from outward movement, as is clearly shown in Fig. 2, an opposite sliding of the bolt, which will take it out of the notch c , serving to release 30 the hasp-plate and toe in an obvious manner. When the box 6 is rocked so as to locate either its closed or open end beneath the hood 9, the flange d' on an arm d of the trunnion-plate 8^a, which is uppermost, will 35 have the notch d^3 therein positioned directly opposite the slot a' , so that if the toe a is entered fully within the slot its inner end will pass into the notch d^3 , and thus adapt the toe of the hasp to hold the box 6 from rotatable movement, which may be further secured by movement of the slide-bolt 11^a, as 40 before explained.

A target or signal 12 in the shape of a plate or any other preferred form is mounted upon a standard 12^a, which passes loosely through the arched hood 9 and at the lower end is pivoted in or on the outer side wall of the mail-box 6, as shown at e in Figs. 2 and 3. It will be seen that the point of pivotal engagement of the standard 12^a with the side wall of the mail-box 6 is some distance above the pivot-bolt 7 when the open end of said mail-box is uppermost, and therefore located beneath and close to the hood 9, which adjustment of the box will project the target 12 some distance above the hood, and it will therefore be rendered plainly visible at some

distance if the target is of proper size and color.

The occupants of the premises to which the mail-box belongs have a key that will release the mail-box and permit it to be turned on its pivot, and the mail-carrier has a like key. In use the carrier of mail, in case there is no mail to take up, should find the mail-box 6 inverted, so that its open end will be lowermost. This disposal of the empty box will draw the standard 12^a downward, so that its pivot connection e will be below the pivot-bolt 7 and the target 12 will be correspondingly lowered, showing plainly that the box is empty. Upon release of the box with an appropriate key the mailman, before the box is swung into an upright position, deposits within the box the mail-matter he may have for it, and then he completes the vertical adjustment of the box, finishing the operation by locking the box in place and then removing his key. From the display of the target 12 that results from the half-revolution of the box 6, as before described, it will be manifest to the persons receiving mail from the box that mail-matter is in the box, from which it may be removed by an authorized party.

The mail-matter that is to be sent to a general mailing-station should be placed in the box 6 and the latter be secured, as before explained, at a time previous to the regular visit or visits of the mailman, who can then take up the deposited mail-matter if such is his duty, or a regular mail-collector who does not distribute mail-matter may attend to the collection of mail from boxes along a route, and it will be apparent that the work of distributing and collecting mail-matter will be safely conducted in an expeditious manner if the improved mail-box is generally adopted.

Having thus described my invention, I claim as new and desire to secure by Letters Patent—

1. The combination with a post or the like, and a hood projected therefrom, of a mail-box closed at one end, and pivoted near its longitudinal center upon the post so that either end of said box may be located close beneath the hood by turning movement of the box, and a lock on the post adapted to secure either end of the box uppermost.

2. The combination with an upright post, and a laterally-projected hood thereon, of a mail-box open at one end, a pivot device on the post and box which adapts said box for free rotatable movement so as to locate the open end of the box close beneath the hood or removed therefrom, a hinged hasp on the post, having a toe which passes through an opening in the post, a locking device adapted to hold the hasp folded and the toe thereon inserted in the opening, and a keeper device on the box engaged by the toe when the hasp is folded.

3. The combination with a post or the like, an arched hood extended laterally from the

post, and a mail-box open at one end and pivoted near its longitudinal center upon the post, so as to permit the open end of the box to be located close beneath the hood by turning movement of said box, of a target device, comprising a signal-plate on one end of a standard, that loosely engages within an orifice in the hood, and at the opposite end thereof is bent to form a pintle, that is rockably held on the box, whereby the movement

of the box will automatically set the signal so as to elevate or depress it.

In testimony whereof I have signed my name to this specification in the presence of two subscribing witnesses.

WILLIAM H. WALKER.
